HEADLIGHT.

Application filed October 24, 1927. Serial No. 228,224.

This invention relates to improvements in the construction of headlights for automobiles.

It is well recognized that many of the fatal accidents that are continually occurring are due to the blinding effect of glaring headlights which make it impossible for the drivers of automobiles to see the road.

It is the object of this invention to produce a headlight that shall be so constructed that it will give good road illumination and at the same time make it possible to divert the light towards the right of the road when meeting an approaching automobile at night and which will also make it possible to throw the light downwardly directly in front of the car so as to get good illumination of the road for slow driving without danger of causing any blinding effect on approaching drivers.

It is the further object of this invention to produce a headlight which shall function in the manner indicated and which shall be of a simple and substantial construction with the parts so arranged that there will be no danger of vibration or the production of a noisy rattling effect.

My invention, briefly described, consists in mounting an ordinary parabolic reflector of the type now in general use so that it can rotate about an axis that makes an angle with the optical axis of the reflector. Means is provided for supporting an incandescent lamp at a point close to the focus of the reflector. When such a reflector is rotated about its axis of rotation, the optical axis will describe the surface of a cone and therefore by rotating the reflector the direction of the rays of light can be altered. The rotation can be readily effected and therefore when a headlight is provided with a reflector mounted in the manner described and with means for rotating it through any desired angle, the direction of the light rays can be changed almost instantly to the position desired.

The reflector in its normal position is located in such a way that the rays of light will be thrown forwardly so as to illuminate the road at the proper distance for high speed driving. By rotating the reflector ninety degrees, the direction of the rays of light can be changed so as to illuminate the right side of the road at a sufficient distance in advance of the car to enable the driver

to proceed at the same speed. When the driving is to be done on city streets or in parks or other places where there is a great deal of traffic, the reflector can be rotated through another ninety degrees so as to throw the rays of light downwardly directly in front of the car, but at a greater angle than normal, so as to illuminate the road only a short distance in advance of the car. This distance, however, being sufficient for the moderate speed at which the driving in such congested parts should be done.

When the rays are directed downwardly, the optical axis of the reflector has such a downward and forward inclination that there will be no glare to interfere with the drivers of approaching automobiles.

In order to more clearly describe the invention and the manner in which I contemplate employing the same, reference will now be had to the accompanying drawings in which the preferred embodiment has been illustrated and in which:

Fig. 1 is a transverse section of an automobile headlight taken on a horizontal plane, so the reflector being shown rotated into the position that it occupies when passing an automobile at high speed;

Fig. 2 is a section taken on line 2—2, Fig. 1; and shows the manner in which the spring is attached to the parts so as to produce a force tending to return the reflector to normal position;

Fig. 3 is a section similar to the section shown in Fig. 2 and shows in a diagrammatic way an electrical means for rotating the reflector;

Fig. 4 is a plan view showing the outline of the illuminated space when the reflectors are arranged for fast driving;

Fig. 5 is a plan view similar to that shown in Fig. 4, which illustrates the location of the illuminated space when the reflectors have been rotated through an angle of ninety degrees;

Fig. 6 is a view showing the downward inclination of the light rays when arranged for fast and for slow driving; and

Fig. 7 is a section taken on a horizontal plane through a reflector and shows the angular relationship between the axis of rotation and the optical axis.

In the drawings reference numeral 1 represents a housing which may be of any approved construction and which has been

shown as a drum type housing, having an in-turned flange 2. A felt strip 3 is attached to the outer surface of flange 2 in the manner indicated. The base 4 of the housing is provided with a central opening 5. A reflector 6 is secured within the housing in a manner which will hereinafter be described in detail. This reflector is provided with a circular flange 7 that projects over the felt ring 3. Secured in the opening 5 is a tubular member 8 whose front end is provided with an outwardly extending flange 9. The interior of the opening in member 8 is threaded near the rear end in the manner indicated by reference numeral 10. A threaded plug 11 has operative engagement with the threads 10 and is provided with a head 12 whose diameter is larger than that of the opening 5. A washer 13 is located between the inner surface of head 12 and the outer surface of the base 4 and when plug 11 is put into place, in the manner shown, and tightened, the tubular member 8 will be rigidly secured to the housing. A pulley 14 is provided with an elongated hub 15 and has a cylindrical opening of the proper size to receive the member 8. Pulley 14 is rotatably secured to the member 8 and held against longitudinal movement by means of the flange 9 and the ring 16. Ring 16 preferably fits quite tightly on the reduced end portion 17 of member 8 so that after it is in place, it will not rotate with respect to this member. A spiral spring 18 has one end secured to the ring 16 at 19 by means of a screw or rivet and the other end of the spring is secured to the pulley 14 by means of a pin 20. It is apparent from Fig. 2 that if the ring 16 is held against rotation and the pulley 14 rotated in the direction of the arrow that the spring will be tensioned and will therefore exert a force tending to return the pulley to its normal position. The normal position is determined by a stop 21 that is secured to the housing and a radial stop 22 that is secured to pulley 14. Spring 18 is normally tensioned to such an extent that when it is not subjected to any external force, the stop 22 will be held against the stop 21 and therefore the normal position of the reflector will be determined by the location of these stops. Secured to the reflector 6 is a tube 23 which is provided with a plurality of fingers 24 that are soldered to the rear surface of the reflector. The tube 23 has an interior diameter of such size that the hub 15 of the pulley can be pressed into the interior of this tube so as to hold the two against relative movement by the friction thus produced. In addition to this, tube 23 may be secured to the pulley by means of solder, or in any other suitable way. It is apparent that whenever pulley 14 is rotated, the reflector will also be rotated.

Referring now particularly to Fig. 7, it will be observed that the surface of reflector 6 is symmetrical with respect to an axis which has been indicated by dot and dash lines 25. This is the optical axis of the paraboloidal reflector. The axis of rotation has been indicated by a dash and dot line 26, which also represents the axis of the hub member 15 and coincides with the axis of the tubular journal 8. It will be observed that this axis of rotation makes an angle w with the optical axis and preferably lies in the same plane as the latter. In actual construction, it is preferred to so arrange these two axes that they intersect each other at the focal point of the reflector. It is now evident that whenever the reflector is rotated about axis 26 the optical axis will describe the surface of a cone in the manner indicated by the dotted line 27. The lamp 28, which is held in place in member 8 by means of an ordinary socket 29, has its filament 30 located approximately at the focus of the reflector. It is well understood that if a source of light is located at the focus of a paraboloidal reflector, all the rays of light will be reflected parallel to the optical axis, which has been indicated by line 25. It is therefore evident that by rotating the reflector, the beam of light will also be rotated so that every light ray describes the surface of a cone. In actual operation the source of light is located either to the front or to the rear of the focal point of the reflector so as to secure proper distribution of the light. The adjustment of the light is effected by means of a screw 31 whose threaded end is operatively connected with the inner end of the socket 29. A spring 32 surrounds the screw and has one end abutting the end of the socket and the other the end of the plug 11 and is under compression so that it will move the socket towards the left (Fig. 1) whenever the screw 31 is rotated so as to unscrew it from the socket. When the screw is rotated in the opposite direction, the socket is moved towards the right. For the purpose of enabling the driver of an automobile to rotate the reflector to the desired extent, a flexible wire 33 has been secured to the pulley 14 and wrapped one or more times around the bottom of the groove 34. This wire extends through a flexible tube 35 to the dash board 36 and terminates in a handle having a ring-like part 37, which can be grasped by the finger of the driver. Handle 37 has a straight shank portion 38 that is provided with a plurality of ratchet teeth 39 which cooperate with a suitable stop in the member 40. When the driver grasps the handle 37 and pulls it towards himself, he will unwind the flexible member 33 from the pulley 14 and rotate the reflector. After the reflector has been rotated to the extent desired, the handle is moved

so that the notches will engage the stop in member 40 and hold the reflector in adjusted position.

The rotating means which has just been described is merely an example of a means for this purpose as it is evident that many other specific means for rotating the reflector may be substituted and as an example of such an equivalent means, I have shown a step by step mechanism which is illustrated in Fig. 3. In this embodiment the pulley 14, instead of having a groove 34, is provided with a plurality of ratchet teeth 41, which are adapted to be engaged by the pawl 42 which is pivotally attached at 43 to a pivoted armature 44. An electromagnet 45 is located with its pole 46 in close proximity to the armature 44, so that when the magnet is energized, the armature will be attracted and will rotate about the pivot 47 through a small angle. As the armature is attracted the pawl 42 will rotate the pulley 14 through the angle represented by one of the ratchet teeth. The winding of the electromagnet terminates in a contact 48 which is adapted to come into electrical contact with the spring 49 that projects from the end of the armature. The spring 50 tends to hold the armature in the position shown in Fig. 3. The electromagnet is connected with one pole of the battery 51 by means of a conductor 52, the other pole of this battery is connected to the armature by means of a conductor 53 which is provided with a push-button 54. When the push-button 54 is closed, the armature will vibrate and rotate the reflector step by step to any extent required. In this modification the spring 18 is dispensed with as the reflector is rotated in the same direction all the time.

The two means for rotating the reflector which have just been described are merely examples as other equivalent means may be employed for this purpose, and applicant does not want to be limited to any specific means for producing rotation, but considers his invention broad enough to cover any arrangement of parts in the optical axis of the reflector can be moved so as to describe the surface of a cone by whatever means this is accomplished.

In Fig. 1 I have shown the housing closed by means of a lens 55 which is held in place by means of a suitable lens ring 56. As this is merely a well known construction no attempt will be made to describe this lens-holding ring in detail, as it is evident that as far as the projection of the light is concerned, the presence or the absence of the lens and lens-holding ring is immaterial.

Referring now more particularly to Figs. 4, 5 and 6, the operation of the device will be described. When the reflector is in normal position with the stops 21 and 22 in engagement, the position of the headlights are

adjusted so that the light will be projected forwardly from the headlights a sufficient distance to properly illuminate the road for fast driving. The illuminated area will then appear somewhat like the one indicated by dotted lines in Fig. 4. In this figure and in Figs. 5 and 6, the paved portion of the road has been indicated by numeral 57. When the lights are in the position shown in Fig. 4, they will cause annoyance to the driver of an approaching automobile. When the driver is about to pass another automobile, he rotates the reflectors through an angle of ninety degrees. This throws the light towards the right of the road into the position indicated by dotted lines in Fig. 5. The approaching automobile can now pass without any interference from the lights and at the same time the driver will have the right side of the road brightly illuminated for a sufficient distance ahead to permit safe driving at high speed. I want to call attention at this point to the great advantage of this arrangement over the ordinary dimming of the headlights. When the headlights are dimmed to a sufficient extent to prevent glare, the illumination is reduced to a corresponding extent and the road is therefore not sufficiently well illuminated to permit the driver to observe danger points along the road, and he is therefore in grave danger of encountering some obstruction that would cause an accident. With the illumination obtained by my device, the right hand side of the road is illuminated as well or even better than when the lights are adjusted as shown in Fig. 4, and the driver has therefore a clear view of the road and at the same time the assurance of not annoying approaching drivers. Where traffic is heavy, the light can be maintained in the position shown in Fig. 5 as long as may be desired, as this gives excellent illumination.

In city driving and in driving through city parks as well as other places where the traffic is heavy and where a moderate speed must be maintained, the reflectors are rotated through an angle of one hundred eighty degrees from normal. This throws the upper rays of light from the line 58 which indicates the normal position to the dot and dash line 59. By this change the distance that the road is illuminated to the front of the car is shortened, but maintained sufficient to enable driving at a moderate speed. With the lights in the position designated in Fig. 6, the road is very well illuminated but the rays are directed downwardly at such an angle that none of them interfere with approaching traffic. It will be understood from Fig. 6 that when the headlights have their reflectors in normal position, the optical axes will be downwardly inclined and that these axes never point in an upward and forward direction.

The showings in Figs. 1 and 7 are taken on a horizontal plane with the reflectors adjusted in a manner corresponding to diagram 5, and this accounts for the apparent upward direction of the optical axes.

From the above explanation taken in connection with the drawings, it will be apparent that I have provided a headlight of a simple construction by means of which the direction of the rays of light can be quickly and easily changed. The mechanism by means of which my invention is carried out is simple and the parts are so arranged that they will not become loose and noisy.

The objects of the above invention, as above intimated, are obtained by the simple expedient of mounting the paraboloidal reflectors so that they can be rotated about axes that lie in the plane of the optical axes but which intersect the latter.

Having thus described my invention what is claimed as new is:

1. A headlight of the character described comprising a substantially cylindrical shaped housing, a tubular journal secured to the housing and extending inwardly thereinto, a lamp socket secured in the tubular journal, a parabolic light reflector having a tubular

bearing secured thereto and mounted for rotation on the tubular journal, said bearing having its axis at an angle to the optical axis of the reflector and intersecting the latter substantially at the focal point and means for rotating the reflector whereby the optical axis will generate the surface of a cone whose apex coincides with the focal point.

2. A headlight of the character described comprising a substantially cylindrical shaped housing, a tubular journal secured to the housing and extending inwardly thereinto, a lamp socket secured in the tubular journal, a parabolic light reflector having a tubular bearing secured thereto and mounted for rotation on the tubular journal, said bearing having its axis at an angle to the optical axis of the reflector and intersecting the latter substantially at the focal point, a stop for limiting the rotation of the reflector, means comprising a spring for normally holding the reflector in position against the stop and means for rotating the reflector against the tension of the spring.

In testimony whereof I affix my signature.

JOSEPH A. ANDERSON.
